UNITED STATES PATENT OFFICE

110,991

DESIGN FOR A COMBINED RADIO AND LAMP

Charles H. Allen, Philadelphia, Pa.

Application May 2, 1938, Serial No. 76,932

Term of patent 14 years

To all whom it may concern:

Be it known that I, Charles H. Allen, a citizen of the United States, residing at Philadelphia, in the county of Philadelphia and State of Pennsylvania, have invented a certain new, original, and ornamental Design for a Combined Radio and Lamp, of which the following is a specification, reference being had to the accompanying drawing, forming part thereof.

In the drawing:

Fig. 1 illustrates a combined radio and lamp adapted to be attached to a bed wherein the upper portion of the radio set is shown in broken lines.

Fig. 2 is a perspective view of Fig. 1 showing the illuminating lamps through the bottom of the radio and the control arm in solid lines.

The characteristic features of my design reside in the underneath lamp opening, the elongated control unit and its association with the radio cabinet.

I claim:

The ornamental design for a combined radio and lamp, as shown and described.

CHARLES H. ALLEN.
